UNITED STATES PATENT OFFICE

2,105,958

REFRIGERATING APPARATUS

Jacob Smilack, Dayton, Ohio, assignor to General Motors Corporation, Dayton, Ohio, a corporation of Delaware

Application November 22, 1934, Serial No. 754,271
Renewed March 11, 1937

3 Claims. (Cl. 62—129)

This invention relates to refrigerating apparatus of the type which condenses moisture from the air and more particularly to apparatus for withdrawing the condensed moisture from said refrigerating apparatus.

In my copending application Serial No. 750,840, filed October 31, 1934, now matured into Patent No. 2,031,550, granted Feb. 18, 1936, I have shown an electrically energized system for removing drip water from a cooling element of a refrigerating system, upon a predetermined accumulation thereof in a collecting receptacle, by vaporizing or evaporating the drip water from the receptacle. While the device or system disclosed in my copending application referred to is highly efficient for refrigerating apparatus of the household food storage type, it has the disadvantage, when incorporated in an air cooling refrigerating apparatus, of discharging the vaporized drip water into the room in which the air is being cooled and consequently dried, thus increasing the humidity of the air within the room and thereby again condensing the moisture in the air on the cooling element. Since the 25 present invention relates to an installation of a refrigerating apparatus in a building or the like wherein drip water from a cooling element of the apparatus cannot be drained from the apparatus by gravity flow to the sewer, I wish to incorporate a portion of the principle disclosed in 30 my copending application for carrying out the following objects of the present invention.

One of the objects of the present invention is to provide an improved method of and apparatus for automatically withdrawing the atmospheric condensation from an evaporator of a refrigerating system where an ordinary gravity disposal apparatus cannot be used and particularly where the drip water of condensation must 40 be elevated above the drip water catching means and/or the evaporator and removed from the room in which the evaporator is located.

Another object of the present invention is to provide an improved means for elevating drip water flowing from a cooling element of a refrigerating apparatus to a point above the cooling element or above the apparatus in which it is located so that disposal of the water may 45 occur by gravity.

A still further object of the invention is to provide a steam pump which is rendered effective automatically and independently of operations of a refrigerating apparatus for elevating water dripping from the cooling element of the refrigerating apparatus to a point above the pump and/or above the cooling element.

Further objects and advantages of the present invention will be apparent from the following 55 description, reference being had to the accom-

panying drawings, wherein a preferred form of the present invention is clearly shown.

In the drawings:

Fig. 1 is a diagrammatic illustration of an installation of a refrigerating apparatus embodying features of my invention; 5

Fig. 2 is an enlarged view, partly in elevation and partly broken away, of a refrigerating apparatus forming a part of the present invention, and 10

Fig. 3 is an enlarged sectional view of parts of the present invention showing an electrical circuit diagrammatically connected with the parts. 15

In an apparatus for cooling rooms in buildings there is generally a considerable amount of moisture condensed on the cooling element of the apparatus which must be removed from the room to effect cooling of the atmosphere therein. In many instances a gravity drain system 20 cannot be installed or is undesirable. My invention is concerned with automatic means for removing the moisture or drip water flowing from the cooling element of a refrigerating apparatus upwardly of the apparatus and out of the 25 room being cooled in an effective manner and particularly independent of operations of the refrigerating apparatus. 15

Referring to the drawings for the purpose of illustrating my invention, the numeral 10 designates in general an apparatus for cooling and circulating air such, for example, as in rooms.

The room cooling apparatus 10 comprises in general a cabinet or casing 11 forming an air treating zone or flue 12 (see Fig. 2). The cabinet 10 is provided with louvers 13 on the front panel thereof to permit air to enter the air cooling zone 12 under the suction of an electrically motor-driven fan 14 whence the air is discharged by said fan through an opening 15, thus circulating the air of the room through the cabinet 10. The air thus circulated through the flue or treating zone 12 is cooled by an evaporator 17 or refrigerant enclosing, air cooling structure comprising a plurality of coils 18 within which a refrigerant is circulated and around which the air passes. The cooling coils 18 are connected in series by means of a pipe 19 and are vertically disposed in the cabinet of the present apparatus. The coils 18 may be supported in any suitable manner in cabinet 10 and are herein shown as being supported by a moisture or drip catching pan 21 carried by the cabinet 10 and forming means for receiving the water, condensed from the air by the air cooling structure and, flowing from the structure by gravity. Refrigerant is circulated through the evaporator 17 by means of a refrigerant liquefying and circulating unit 23, of which the evaporator 17 forms a part there- 40

of, under the control of a suitable expansion 45

<p

valve 24. Refrigerant is delivered to the coils 18 through a liquid refrigerant pipe 26 and is withdrawn through a suction pipe 27. The refrigerant liquefying and circulating unit 23 also includes a compressor 28 operatively connected with a motor 29 by suitable belt and pulley connections 31. Compressor 28 compresses the gaseous refrigerant and delivers it to a condenser 32, through a pipe 33, where it is cooled in any suitable manner. The gaseous refrigerant is liquefied in the condenser 32 and flows into a receiver 34 from where it is delivered under pressure through the liquid refrigerant pipe 26, to the evaporator. A thermostat 36, is attached to the gaseous refrigerant return pipe 27 and, has a pipe 37 connecting the same to a bellows 39 forming a part of and serving to operate an automatic switch 40, of conventional and well-known design, which connects the motor 29 to the power lines 42. The thermostat 36 thus controls the operation of switch 40 in response to the temperature of the pipe 27 to thereby maintain the evaporator 17 at the proper air cooling temperature and to prevent refrigerating action in the pipe 27 beyond the air treating zone. In a room cooling apparatus as disclosed, considerable atmospheric moisture will collect on the evaporator 17, due to the cooling action of the evaporator, and will flow therefrom into the catch pan 21. The catch pan 21 is connected to a steam pump or the like device, located therebelow and generally indicated by the reference character 45, which will now be described.

The device 45 includes a pipe or conduit 46 connected with the drain opening provided in the lower portion of pan 21 (see Fig. 3). The pipe 46 is formed integral with and may support the device 45. The casing 47 of the device 45 may be constructed of any desired or suitable material to carry out my invention and is formed to provide a valve seat 48 at the lower end of the conduit 46 or at the inlet to the casing 47. A valve 49 cooperates with the seat 48 and has a stem 51 extending to the exterior of the casing 47. The valve 49 is normally open and a magnet 52, of any conventional or suitable design, is associated with the valve stem 51 and is adapted to draw the stem 51 upwardly thereinto when energized to cause valve 49 to close against seat 48 to thereby close the normally open inlet to casing 47. The casing 47 of device 45 forms a chamber, receptacle or trap 55 for the reception of drip water from conduit 46. A threaded opening 56 in a side wall of casing 47 is closed by a plug 57 preferably constructed of insulating material such, for example, as bakelite or porcelain and has two electrodes 58 and 59 molded or sealed therein. The electrodes 58 and 59 extend entirely through the plug 57 so as to protrude into the receptacle or trap 55 and so as to permit attachment of electric wires to their outer ends. An outlet opening 61 leading from a lower portion of trap 55 is connected by an elbow casing 63 housing a check valve 64, of any suitable construction, adapted to rest on seat 62. The elbow casing 63 is connected, in any suitable manner, with a pipe 65 and the valve 64 is normally closed upon its seat 62, thus preventing communication between trap 55 and pipe 65. The pipe 65 extends above the room cooling apparatus 10 and particularly above the trap 55 or evaporator 17 to a point adjacent to or within the ceiling of the room in which the apparatus 10 is located (see Fig. 1). The pipe 65 then extends horizontally beyond other rooms of the building to a

point where it may extend downwardly such, for example, as an elevator shaft or the like.

Thermally associated with or secured to, but electrically insulated from, the bottom wall of receptacle or trap 55, in any suitable manner, there is located an electrical heating unit 67 containing a resistance winding 68 having a connection with each of the lead-in terminals 69 and 71 of the unit 67. A switch unit including a heater comprising an electrical resistance wire 73 spaced from and adapted to heat a bimetallic thermostat element 74 is shown as mounted on the bottom of pan 21. As shown in Fig. 3 of the drawings the switch unit is preferably carried by insulating blocks 76 and 77. The resistance or heater wire 73 is adapted to heat the thermostat switch element 74 to cause movement thereof and is provided with terminal connections 78 and 79. The thermostat element 74 is provided with a terminal 81 at its stationary end and carries a contact 82 on its movable end which contact is adapted to engage a stationary mounted contact 83. It is to be understood that the switch unit just described may be located in a box or other enclosure and mounted wherever desired.

The electrical circuit connected in parallel with the power supply conductors 42 and leading to the control switch 40 and motor 29 of the refrigerating liquefying and circulating unit 23 will now be described. Referring to Fig. 3 of the drawings, wherein this electrical circuit is diagrammatically illustrated, there is a wire 91 connected with one of the power supply conductors 42 (see Fig. 1) which wire leads to the terminal 92 attached to the electrode 58. A branch wire 93 connects the terminal 81 of thermostat 74 with the wire 91. A wire 94 connected to the other of the power supply conductors 42 (see Fig. 1) is attached to the terminal 95 leading to one end of a coil or winding (not shown) contained in the magnet 52. The other end of the coil or winding of magnet 52 is secured to the terminal 96 and this terminal has a wire 97 leading therefrom and connected to the terminal 79 of the resistance heater wire 73. Wire 97 has a branch wire 98 which is attached to the terminal 69 of the heater unit 67 which leads to the resistance wire 68 enclosed in the unit 67. A wire 99 is attached to the binding post or terminal 78 of the resistance wire 73 and is connected to the terminal 101 of the electrode 59. Another wire 102 extends from the stationary contact 83 of the switch unit to the terminal 71 leading to the resistance heater 68 of the unit 67.

The electrode 58 is connected at its binding post terminal 92 by wire 91 with the source of electrical supply at all times and the electrode 59 is likewise connected with the source of electrical supply through wire 99, resistance wire 73, wire 97, magnet 52 and wire 94. This causes the electrodes to be charged with electrical energy at all times and maintains an electrical potential between the electrodes 58 and 59. However, since these electrodes are insulated from one another there is ordinarily no current flowing between them and no electric energy is used. In practicing my invention, as will hereinafter be more fully described, it will be understood that the heater wire 73 for the thermostat switch is preferably of greater resistance to flow of electric energy than the drip water in receptacle or trap 55 so that when the electrodes 58 and 59 are bridged by the water, the amount of current passing through wire 73 is sufficient to cause

heating of this wire for influencing or effecting the thermostat 14.

As an example of the installation of a refrigerating apparatus or system to which my invention is particularly applicable, I have shown in Fig. 1 of the drawings a cross section of an office building or apartment divided into a plurality of rooms 105, 106, 107 and 108. In this arrangement the room or air cooling apparatus 10 is shown as being located in the room 105 for cooling the air therein while the compressor, motor and condensing unit 23 is shown located in the room 108 which may be the basement of the building. In many instances the place where the room cooling apparatus is located is owned or occupied by one person, while the room immediately below the room where the apparatus is located is owned or occupied by another, which would prevent the installation of a gravity drain pipe and other pipes of the apparatus leading from the room cooling apparatus to the compressor-condenser-unit. In this case it would be necessary to extend the pipes 26, 27, 37 and 65 above the drip water trap 55, pan 21 and evaporator 17 to the top of room 105 and across room or apartment 106, which may be a hallway and direct the pipes downwardly through some other apartment or through an elevator shaft beyond and at one side of room 107 to connect said pipes to the compressor-condenser unit 23. In the arrangement illustrated and described, it is obvious that the installation of a gravity drain device for removing the drip water flowing from the evaporator 17 of the apparatus 10 is impossible and that some other device must be provided to remove the drip water from the apparatus 10 and room 105. It will be noted that I have provided a device for this purpose and its operation will now be described.

When moisture or water drips from the evaporator or cooling element 17, located in the cabinet 11 of the apparatus 10, for any reason whatsoever, this moisture or drip water is caught in the pan 21 and is conveyed by the pipe or conduit 46 into the chamber or trap 55. The drip water is trapped or collects in the lower portion of chamber 55 and when a sufficient amount has been collected, the level of the water rises in the trap 55 so that it contacts or bridges both of the electrodes 58 and 59. Since the electrodes 58 and 59 are energized, the drip water upon bridging same causes a small amount of electric energy or current to flow from one electrode to the other through the water. My arrangement is such that the amount of current flowing through the drip water is sufficient to cause heating of the resistance wire 73 but preferably no appreciable heating of the water bridging the electrode. The amount of electric energy or current capable of being conducted from one electrode to the other thereof, through the water, being in accordance with this invention, sufficient to cause the circuit connecting the electrodes with the source of electric supply to be closed through the magnet 52 and resistance wire 73. Closing of this circuit through wires 94, 97, 99 and 91 causes both the magnet 52 and resistance wire 73 to be energized. The magnet 52 thus attracts and moves the stem 51 of valve 49 upwardly to seat the valve 49 against its seat 48 and to close the chamber 55 from the conduit 46. The resistance wire 73 upon being energized generates heat and radiates this heat against the bimetallic thermostat 74. Heating of thermostat 74 causes its free or contact carrying end to move away from the

heater resistance wire 73 and towards the stationary contact 83. The contact 82, carried on the free or movable end of thermostat element 74, engages the contact 83, thus completing or closing the electric circuit leading to the heater 67. It will be understood from the disclosure and description thereof that the circuit to the heater 67 just described is made through a plurality of metallic elements of good conducting material and entirely independent of the water connection between the electrodes 58 and 59. Therefore, electric energy is readily conducted to the resistance element 68 located in heater unit 67 without having to pass through or being impeded by other resistance means or elements in the electric system.

When the circuit has been completed through electrodes 58 and 59 by water bridging same, the magnet 52 is energized and this magnet causes valve 49 to seat against its seat 48 for closing off the inlet conduit 46 from the drip water receiving chamber or trap 55. The circuit is such that the valve 49 is caused to remain closed as long as the contact 82 of thermostat 74 is in engagement with the contact 83 for directing current to the heater unit 67. The heater unit 67 and its resistance heating wire 68 may be of any well known or suitable construction and arrangement as to generate considerable heat and are associated with the drip water receptacle or trap 55 in such a manner as to rapidly transfer or conduct this heat to the water. The arrangement is such that, or since other provisions obviously within the realm of my invention can be made, such, for example, as a secondary electric circuit of low voltage through the drip water to insure that very little electric current will pass through the water, when the water bridges the electrodes 58 and 59, blowing of fuses in the circuit will be prevented. Thus, provisions to insure that the thermostat heater 73 generates only a small amount of heat sufficient to cause operation or movement of the bimetallic thermostat 74 as compared to the amount of heat generated by the heating resistance element 68 are obvious to one skilled in the art.

Consequently, when the heater 67 is rendered effective, drip water in receptacle or trap 55 is rapidly heated, without directly contacting the heating resistance wire 68, and is caused to vaporize or evaporate.

Pressure, resulting from vaporization of the drip water in trap 55, builds up in the trap, due to the check valve 64 and valve 49 being in closed position, and upon reaching a predetermined high limit, forces the check valve 64 open. Thus the device and the pressure of the vaporized moisture or drip water therein forms a steam pump and forces water from the chamber 55 through conduit 61 and beyond the check valve 64. Water trapped in the fitting 63 and the pipe 65 beyond the valve 64 accumulates and rises in pipe 65 to a height sufficient to then permit the water to flow by gravity through the downwardly directed portion of pipe 65 to a drain connection located in the cellar floor of the building. It is to be understood that the check valve 64 may be opened and closed intermittently as long as heat is being applied to water in the receptacle or trap 55 to cause pressure therein to build up to a point to overcome the weight of the valve 64 and the column of water beyond the valve.

When the contacts 82 and 83 are closed, to conduit electric energy directly through good me-

talic conductors, to the heater 67, the circuit between the electrodes 58 and 59, through wire 94, magnet 52, wire 97, resistance wire 73, wire 99 and wire 91 remains closed as long as there is sufficient water in the trap 55 to bridge or contact both electrodes. As soon as sufficient water has been vaporized to force water from the trap 55 to cause the level thereof to be lowered or to fall below electrode 58, the electrical circuit leading to heater wire 73, through the electrodes 58 and 59 from wires 91, 99 and 97, magnet 52 and wire 94, will be broken thus de-energizing the heater wire 73. The heater wire 73 therefore ceases to generate heat and the bimetallic thermostat 74 begins to cool and after a predetermined period of time, according to the arrangement and location of the thermostat, the bimetallic member 74 will move back into its normal position adjacent the heater wire 73. This movement of thermostat 74 is thus delayed or prolonged for a predetermined length of time, depending upon the time required to cool the same, and the contacts 82 and 83 remain closed for a predetermined period of time after the circuit to the thermostat heater wire 73 has been broken by the lowering of the water level below electrode 58. The heater 67 is thereby caused to continue its heating effect of the water in the trap 55 until the contacts 82 and 83 are separated by the cooling and consequently movement of thermostat 74 whereafter the magnet 52 is de-energized and valve 48 is opened to permit water accumulated in pan 21, during the drip water removing operation as described, to flow therefrom through conduit 46 into the trap 55 to again render the water removing system effective.

The prolonged breaking of the circuit to heater 67, as accomplished in the manner described, is desirable for the reason that it insures removal of substantially all of the drip water contained in the trap 55 during a single period of effectiveness of my steam pump or vaporizing system. Ordinarily, therefore, a considerable length of time will elapse before the level of drip water attains a sufficient height to again energize the electric steam pump or vaporizing system and operations of parts thereof are thus minimized. The lapse of time between operations of energizing my electric steam pump or vaporizing system can be regulated to suit any particular refrigerating apparatus installation by varying the distance between the bottom of the trap 55 and the electrode 58 so that the receptacle or trap 55 will hold any desired amount of water in accordance with the period of prolonged cooling and consequently movement of thermostat 74 to normal position.

It will be seen that I have provided an effective means for elevating drip water, flowing from an evaporator of a room cooling apparatus, to a point above the apparatus, where the water may then flow by gravity to a drain, automatically and without the user's attention. I thus eliminate the necessity of manually emptying a drain pan of a room cooling apparatus and this is particularly advantageous in apartments or office buildings where at times there is no attendant in the building.

While the form of embodiment of the invention as herein disclosed constitutes a preferred form, it is to be understood that other forms

might be adopted, all coming within the scope of the claims which follow.

What is claimed is as follows:

1. In combination, a portable unit including an element which dehumidifies air and which has water dripping therefrom, means for catching the drip water from said element, said drip water catching means having an inlet for conducting the drip water thereinto and an outlet adapted to conduct drip water therefrom, means connected to a source of energy for creating a pressure in said drip water catching means to cause removal of drip water upwardly therefrom through said outlet, said last named means being normally ineffective and rendered effective automatically in response to the flow of a predetermined amount of drip water from said element to said catching means, and means also deriving its energy from said source of energy for said pressure creating means for prolonging the effectiveness of said drip water removing means for a predetermined period of time after the accumulation of drip water in said catching means has been diminished beyond the point for initiating effectiveness of said drip water removing means.

2. In combination, a portable unitary structure including an element which dehumidifies air and which is adapted to have water dripping therefrom, means connected to a source of energy for circulating a fluid through said element to cause same to dehumidify the air, means for catching the drip water from said element, said drip water catching means having an inlet for conveying the drip water thereinto and an outlet adapted to conduct drip water therefrom, means for closing said inlet, means for creating a pressure in said drip water catching means, said last named means including means deriving its energy from said source of energy for said fluid circulating means, and a conduit connected to said outlet and extending upwardly above said drip water catching means, said pressure creating means being effective to force water from said drip water catching means through said conduit.

3. In combination, a portable unitary structure including an element which dehumidifies air and which is adapted to have water dripping therefrom, means connected to a source of energy for circulating a fluid through said element to cause same to dehumidify the air, means for catching the drip water from said element, said drip water catching means having an inlet for conveying the drip water thereinto and an outlet adapted to conduct drip water therefrom, means for closing said inlet, means for creating a pressure in said drip water catching means, said last named means including means deriving its energy from said source of energy for said fluid circulating means, and a conduit connected to said outlet and extending upwardly above said drip water catching means, said pressure creating means being normally ineffective and rendered effective automatically in response to the flow of a predetermined amount of drip water from said element to said catching means to force water from said drip water catching means through said conduit.
